United States Patent Office

Des. 197,596
Patented Mar. 3, 1964

197,596

DRIVE-IN RESTAURANT

Lauris L. Beigh, 3616 SW. Roxbury, Seattle, Wash.

Filed Feb. 25, 1963, Ser. No. 73,703

Term of patent 3½ years

(Cl. D13—1)

I claim:

The ornamental design for a drive-in restaurant, as shown.
